UNITED STATES PATENT OFFICE.

BERNARD LYNN McNERNEY, OF MINNEAPOLIS, MINNESOTA.

WRENCH.

Application filed October 22, 1924. Serial No. 745,133.

My invention relates to improvements in adjustable wrenches of the type having a jaw-carrying head equipped with a handle hinged thereon, the tilting of the handle 5 with respect to the head serving to open and close the jaws.

An object of the invention is to provide a wrench of the present nature having oppositely movable jaws and novel means for 10 shifting the same, said means being operated through the handle by which the tool is manipulated.

Another object is to supply a quickly adjustable wrench of the instant type that is 15 simple, durable, and relatively inexpensive in construction.

With the foregoing and other objects in view, which will appear in the following description, the invention resides in the novel 20 combination and arrangement of parts and in the details of construction hereinafter described and claimed.

In the drawings, Fig. 1 is a side elevation of a wrench embodying my invention; 25 Fig. 2 is a bottom edge view thereof; Fig. 3 is a front edge view of the same; Fig. 4 is a sectional view taken on the line 4—4 of Fig. 1; and Fig. 5 is a similar view taken on the line 5—5 of Fig. 2.

Referring to the drawing, it will be observed that my improvement includes a head A and a handle B, the former consisting of head members a' , a^2 . The head member a' comprises a shank 10 and a right-angular jaw 11 reaching forwardly therefrom. Said shank 10 is recessed at its forward edge from one side edge to the other to form a way 12. Extending transversely through the shank 10 at the rear and in parallelism with said way 12 is an elongated opening 13 that communicates with said way 12. The rear portion 10^a of the shank 10 is reduced in thickness as compared with the thickness of the forward portion thereof. A rack C is formed on said shank 10, the same including a rib 14 reaching forwardly from the rear wall of the opening 13, between the upright margins thereof, also teeth 15 formed on the front side of said rib. The head member a^2 consists of a shank 16 and a right-angular jaw 17 reaching forwardly therefrom. Said shank 16, complementing the way 12, slidably fits therein. Thus fitted together the head members a' , a^2 slide one on the other in direction to bring the jaws 11, 17 together, or to separate the same.

Formed on the rear edge of the shank 16 and reaching into the opening 13 is a rack, the same consisting of rearwardly extending teeth 18.

The handle B is bifurcated at its forward end to form branches 19, which straddle and fit snugly against the sides of the reduced shank portion 10^a (Fig. 4). At the tips of these branches 19 and on the inner sides thereof are opposed annular bosses 20. The peripheries of these bosses 20 bear at their forward and rearward sides against the upright margins of the forward and rear walls of the opening 13, while the faces of said bosses bear marginally against the sides of the rack C and teeth 18. Interposed between the bosses 20 is a gear 21 meshing at its forward side with the teeth 18 on the shank 16 and at its rear side with the teeth 15 on the shank 10. This gear 21 is secured with respect to the handle B by means of a key-bolt 22 which reaches axially through the gear 21 and bosses 20 and serves to tie the handle branches 19 against spreading. With said gear 21 fixed to the handle B and meshing with the teeth 18, 15 on the shanks 16, 10, it will be understood that the tilting of the handle B on the head A in one direction will result in the opening of the jaws 11, 17 and a reverse tilting movement of said handle will cause said jaws to close. Upon manipulation of the tool, the bosses 20 guide the gear 21 in the opening 13 and together with those portions of the branches 19 next adjacent thereto, rigidly hold the handle B against edgewise and sidewise movement with respect to the head A.

In applying the tool to an object, the user "breaks" the structure on the axis of the bolt 22 to open or close the jaws 11, 17 and thereby suit the dimensions of the object. Embracing the object, said jaws are gripped thereagainst by swinging the handle B on the head A in a direction to close the jaws. Continuing the application of force upon the handle B to further swing the same, the jaws 11, 17, which are caused to grip the object with force in proportion to that applied to the handle, transmits the turning force of said handle to said object. Reversing the swing of the handle B releases the jaws 11, 17 for a new grip.

From the foregoing, the simplicity of structure, quick acting characteristics of the wrench, and the effectiveness and durability thereof will be readily appreciated.

Changes in the specific form of my invention, as herein disclosed, may be made within the scope of what is claimed without departing from the spirit of my invention.

Having described my invention, what I claim as new and desire to protect by Letters Patent is:

1. In a wrench, a pair of head members, each comprising a shank and a right-angled jaw reaching forwardly thereof the shank of one member being formed with a way in the front edge thereof and also formed with an elongated opening therethrough at the rear thereof, said opening paralleling said way and communicating therewith, the shank of the second member fitting said way in the shank of the first member and slideable therein, there being rearwardly projecting rack teeth at the rear edge of said shank, there being rack teeth projecting forwardly from the rear wall of the opening in the shank of the first member, a gear located in said opening and meshing at its forward and rear sides with said first and second rack teeth respectively, a handle bifurcated at one end thereof, the branches of said handle straddling the shank of said first member and formed with opposed annular bosses on the inner sides thereof, the rims of said bosses riding against the outer margins of the forward and rear walls of said elongated opening and the margins of the faces of said bosses bearing against the ends of the rack teeth on both shanks, said gear being fixed

to the handle between and in axial alinement with the bosses thereon, said handle serving to turn and guide the gear and said gear serving, through coaction with said rack teeth, to relatively shift the head members and open and close said jaws.

2. In a wrench a pair of head members, each comprising a shank and a right-angled jaw reaching forwardly thereof, the shanks of said members being relatively slideable one on the other, the shank of one member being formed with an elongated opening traversing the same and paralleling the line of relative movement of said members, there being rack teeth on the shank of the second member, there being rack teeth on the first member arranged along the rear wall of said elongated opening spaced apart from and opposing said rack teeth on the second member, a handle bifurcated to snugly straddle the first member, a gear within said elongated opening meshing at its opposite sides with said rack teeth and secured to said handle, there being an annular boss at the inner side of one of the branches of said handle, the rim of said boss riding against the opposite walls of said opening, said handle serving to turn said gear and said gear serving, through its coaction with said rack teeth to relatively shift said members and thereby open and close the jaws.

In testimony whereof, I have signed my name to this specification.

BERNARD LYNN McNERNEY.
